UNITED STATES PATENT OFFICE.

JOSEPH S. GOLD, OF JACKSON, OHIO.

TELEPHONE-SHELF.

No. 806,339.

Specification of Letters Patent.

Patented Dec. 5, 1905.

Application filed May 20, 1904. Serial No. 208,891.

To all whom it may concern:

Be it known that I, JOSEPH S. GOLD, a citizen of the United States, residing at Jackson, in the county of Jackson and State of Ohio, have invented new and useful Improvements 5 in Telephone-Shelves, of which the following is a specification.

My invention relates to improvements in telephone-shelves, and pertains more particularly to a shelf which is readily attached to the ordinary telephone-box.

The object of my invention is to provide a shelf for a telephone which is readily attached to or detached from a telephone and provided with means for securing a tablet thereto and so that the tablet may be readily removed and replaced when the same has been used up.

Another object of my invention is to provide 20 means for supporting the receiver when it is desired to hold the phone and also providing means for preventing the accidental placing of the receiver on said support instead of the desired hook when one is through 25 with the phone.

A still further object of my invention is to provide a more simple, cheap, and effective shelf of this character than has heretofore been produced.

30 In the accompanying drawings, Figure 1 is a perspective view of my improved shelf attached to a telephone-box, showing the receiver held thereon for the purpose of holding the phone. Fig. 2 is an enlarged plan view of my improved shelf detached. Fig. 3 is a bottom plan view of Fig. 2.

Referring now to the drawings, A represents a piece of veneered wood, which absolutely prevents the same warping or splitting and 40 provides a much more finished look at less cost. Passing through said shelf are two bolts B and B', which have their heads b and b' embedded below the upper surface of the shelf, thus forming practically a smooth upper face to the shelf. The said bolts pass through elongated slots c and c' in the clamping members C and C', and thus the same are longitudinally adjustable and adapted to engage or to be adjusted to engage the edges of 45 the telephone-box, and thus the same is adapted to be attached to boxes of different widths. The said bolts B and B' carry on their outer ends on the outside of the clamps thumb-nuts D and D', and thus the shelf is 55 firmly clamped in any adjusted position on

the top of the telephone-box. The right-hand end of the shelf A is provided with an enlarged portion E, which forms a support for the memorandum-tablet F, and the same being considerably larger than the tablet 60 gives a partial support for the wrist or arm of the writer. The upper end of said enlarged portion E is provided with a saw cut or slit e, which extends from the upper edge a of the shelf, and extending across the upper 65 face of said enlarged portion E is a metal strap G, which has one end g turned down around the edge e' of the enlarged portion and is provided with upwardly-depressed portions g', which are adapted to be driven into the bottom of the shelf, and thus firmly hold the strap thereon. The opposite end g' of the strap G passes downwardly through the saw cut or 70 slit e and is provided with the upwardly-depressed portion g'', which is driven into the 75 bottom of the shelf and firmly holds the strap against any possible movement. The said strip G is preferably of a thin flexible metal, and thus the back of the tablet F can be readily slipped under said strip and firmly 80 held thereunder, yet allowing of the ready removal of the same for replacing it when it has been used up. The opposite end of the shelf A is provided in its outer edge a' with an elongated slot H, which is of such a size to 85 readily receive the receiver, and thus the same is supported when it is desired to hold the phone, as in phones of this character there is no way of supporting the receiver should you desire to hold the phone when absent therefrom. In order to prevent the accidental 90 misplacing of the receiver in said slot instead of the proper hook when you are through with the phone, I provide a cover I, which is hinged to the shelf A at i, which by force of 95 gravity is normally held over said opening or slot H. The said cover is so hinged to the shelf that the same cannot be swung up to a vertical position, but far enough to allow of the ready placing of the receiver in the slot, 100 and the cover is then supported by the receiver. When the receiver is removed, the cover by force of gravity covers the slot, and one could not thoughtlessly place the receiver in the slot, as the cover would first have 105 to be raised. As shown, the cover I is formed of metal and is provided with openings I', and passing through said openings are staples J, which are driven into the shelf A, and said staples are driven far enough into the 110

shelf to cause the inner edge i^2 to engage the shelf, and thus prevent it from swinging all the way over, as heretofore described.

Having thus described my invention, what I claim, and desire to secure by Letters Patent, is—

1. The combination with a telephone having a cut-out receiver-holder, of a base attached thereto and having a slot therein, and means for normally closing said slot to prevent the accidental placing of the receiver therein.

2. The combination with a telephone having a cut-out receiver-holder, of a base attached thereto and having a slot therein, and a plate normally closing said slot to prevent the accidental placing of the receiver therein.

3. The combination with a telephone having a cut-out receiver-holder, of an attachment adapted to support the receiver independent of the cut-out holder, and means for preventing the accidental placing of the receiver in the support.

4. The combination with a telephone having a cut-out receiver-holder, of a base attached thereto and having a slot therein, and a swinging plate normally closing said slot to prevent the accidental placing of the receiver in said slot.

5. An attachment for telephones, comprising a base having a slot on one end for holding the receiver, and a hinged plate normally held over said slot, and means for preventing said plate from being swung backward over the base.

6. The combination with a telephone having a cut-out receiver-holder, of a base detachably secured thereto and having a slot therein, and a swinging plate normally closing said slot to prevent the accidental placing of the receiver in said slot.

7. An attachment for telephones, comprising a board having a slot in one end, a plate normally closing said slot, and staples passing through said plate and secured to said board and so positioned that the plate cannot be raised to a vertical position whereby the force of gravity normally holds the same over said slot.

8. The combination with a telephone having a cut-out receiver-holder, of an attachment having a slot therein for supporting the receiver independent of the cut-out holder, and a plate normally closing said slot and adapted to prevent the accidental placing of the receiver in said slot.

9. The combination with a telephone having a cut-out receiver-holder, of a base attached thereto and having a slot for receiving the receiver, a hinged plate normally held over said slot and means for preventing said plate from being swung backward over the base, whereby the accidental placing of the receiver in the slot is prevented.

10. An attachment for telephones, comprising a base having a slot therein for holding the receiver, a plate hinged to said base adjacent the slot, and means for preventing the said hinged plate from being raised to a vertical position whereby the same is normally held in a horizontal position covering said slot.

11. An attachment for telephones, comprising a base, means carried by the under side thereof for clamping the same to the telephone-box, one end of said base having a slot for holding the receiver, a plate hinged to said base adjacent the slot and normally closing the same, and means for preventing the said hinged plate from being raised to a vertical position whereby the same is normally held in a horizontal position covering said slot.

12. An attachment for telephones, comprising a base, means carried by the under side thereof for clamping the same to the telephone-box, one end of the said base having a slot extending from the edge inwardly and adapted to receive the receiver, a plate normally held in a horizontal position covering said slot, and the outer edge being flush with the edge of the base, and means for preventing the said hinged plate from being raised to a vertical position, whereby the same is normally held in a horizontal position covering said slot.

13. The combination with a telephone having a cut-out receiver-holder, of an attachment comprising a board and adapted to be clamped to the telephone-box, said board having a slot for holding the receiver, and a plate for normally closing said slot, whereby the accidental placing of the receiver in the slot is prevented.

In testimony whereof I have hereunto set my hand in the presence of two subscribing witnesses.

JOSEPH S. GOLD.
